Primary Examiner — Mary Shannon Malley*Assistant Examiner* — Christopher John Suarez La Rosa(74) *Attorney, Agent, or Firm* — The Belles Group, P.C.**CLAIM**

The ornamental design for a barber chest carrier, as shown and described.

DESCRIPTION

FIG. 1 is a front-right perspective view of a barber chest carrier showing the claimed design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The dash-dash broken lines depict portions of the barber chest charrier that form no part of the claimed design. The long dash-short dash broken lines depict the bounds of the claim. The remaining short dash-short dash broken lines depict stitching that does not form part of the claimed design.
